UNITED STATES PATENT OFFICE.

GEORGE M. KNEUPER, OF NEW YORK, N. Y.

FILTER-CELL.

1,148,237.

Specification of Letters Patent.

Patented July 27, 1915.

Application filed July 31, 1913. Serial No. 782,206.

To all whom it may concern:

Be it known that I, GEORGE M. KNEUPER, a citizen of the United States, and a resident of the borough of Brooklyn, county of 5 Kings, city and State of New York, have invented certain new and useful Improvements in Filter-Cells, of which the following is a specification.

My invention relates to filter cells and has 10 for its object to so construct a filtering cell that its filtering material will retain its efficiency for a long time, may be renewed readily when required, and will stand a very high pressure.

15 Another object of my invention is to provide a very strong and durable filter cell having special devices for insuring a tight joint of the cell when placed in a filter.

The invention will be fully described hereinafter, and the features of novelty pointed 20 out in the appended claims.

Reference is to be had to the accompanying drawings, in which—

Figure 1 is an elevation of my improved 25 filter cell, with parts broken away; Fig. 2 is a central vertical section showing the cell within a filter; Fig. 3 is a horizontal section on line 3—3 of Fig. 2; and Fig. 4 is a perspective view of one of the rubber washers 30 used in conjunction with my improved filter cell.

The cell comprises an apertured core composed of a number of spaced longitudinal bars A connected by rings B. Around this 35 core I place or wrap the filtering material C, preferably a sheet of fibrous material in two or more layers. The top and bottom edges of the filtering material are about flush with the ends of the core. At each end I employ 40 a rubber washer D having a transverse portion D' adapted to extend inwardly over the end faces of the core, as shown in Fig. 2, the outer cylindrical portion of the washer surrounding the edge portions of the filtering 45 material C. A wire or other clamping device E is applied to each of the washers D preferably immediately above the lower end ring B and below the upper end ring B, to force the washer D and the filtering material C tightly against the core. Around the filtering material C is placed an elastic per- 50 vious sleeve F, preferably consisting of a band or strip of elastic webbing or other suitable pervious material wound helically around the filtering layer C, the ends of said band being secured in any suitable manner.

Thus in Fig. 1 the upper end of the band is shown secured temporarily by means of a pin F' (which is removed later on), while the permanent fastening is obtained by placing the ends of the band between the filtering layer C and the respective washers D, so as to hold the band by the clamping action of the wire E. The elastic sleeve F is surrounded, with an intervening space, by 60 a perforated cylinder or jacket G made of sheet metal. The preferred way of holding this cylinder in place consists in forming it with outwardly doubled edges G' over which is slipped a longitudinal connecting strip H 65 having inwardly bent edges and made of sheet metal or other suitable material. The strip H extends the full length of the jacket G, and the washers D project beyond the ends of the jacket. 70

The filter-cell constructed as described above, is used in connection with any suitable filter. In the example shown, the cell is clamped between the bottom J' and the cover J² of a filter J to which the water or 80 other liquid to be filtered is supplied through a central perforated pipe K, while the filtered liquid passes out through a faucet L. The cover is held down by a nut M screwing on the upper end of the pipe K. The rubber 85 washers D produce a tight joint at the upper and lower edges of the filter-cell. 75

In operation, as the water or other liquid passes outwardly through the filtering layer C, said layer tends to bulge out, and the 90 elasticity of the sleeve F allows the filtering layer to yield in this direction. When the supply of liquid is shut off, the elastic sleeve will contract at once and again press the filtering layer C firmly against the core. This 95 inward or contractile movement of the filtering layer will greatly assist in dislodging from the inner surface of said layer, any deposit that may have been formed thereon, and this feature will considerably lengthen 100 the useful life of the filtering material. Should the liquid be supplied at a pressure temporarily exceeding that for which the elastic sleeve F is designed, such sleeve will be relieved of excessive strain by contact 105 with the surrounding cylinder G. While not absolutely rigid, this cylinder is of course much more resistant than the elastic sleeve F.

One of the principal advantages of the elastic band F is that thereby the filtering material is always firmly pressed against the core, and the soiled surface being thus held 110

in rigid position can be cleaned readily and efficiently by means of a spray of water or brush without danger of injury.

The filtering material C being put on in 5 layers, which in course of time or use wear away, the following layers, due to the elastic or contractile qualities of the band F, are again pressed against the core and thus keep the cell in perfect working order until the 10 last layer is worn away. Moreover, this contractile tendency prevents the cell from absorbing water in a very great measure, which facilitates its drying out completely when not in use, whereby its capillarity is quickly 15 restored. The elasticity thus given the cell has the further advantage of absorbing the shock or "water hammer," which shock impairs the efficiency of filters generally.

Various modifications may be made without departing from the nature of my invention as set forth in the appended claims.

I claim:

1. A filtering cell comprising an apertured core, a layer of filtering material surrounding said core, a pervious elastic sleeve surrounding the filtering material, and a relatively rigid jacket surrounding said sleeve.
2. A filtering cell comprising an apertured core, a layer of filtering material surrounding said core, a pervious elastic sleeve surrounding the filtering material, a split jacket surrounding the sleeve, and means for connecting the edges of said jacket.
3. A filtering cell comprising an apertured core, a layer of filtering material surrounding said core, a pervious elastic sleeve surrounding the filtering material, a split perforated jacket surrounding the sleeve and 40 having outwardly doubled edges, and a connecting strip engaging said edges.
4. A filtering cell comprising an apertured core, a layer of filtering material sur-

rounding said core, and a sleeve formed by a strip of pervious elastic material surrounding 45 said filtering material helically.

5. A filtering cell comprising an apertured core, a layer of filtering material surrounding said core, and a sleeve of elastic textile material surrounding said filtering 50 material.

6. A filtering cell comprising an apertured core, a layer of filtering material surrounding said core, washers extending over the ends of the core and surrounding the adjacent portions of the filtering material, and means for clamping the washers and filtering 55 layer against the core.

7. A filtering cell comprising an apertured core provided with rings at its ends, 60 a layer of filtering material surrounding said core, washers extending over the ends of the core and surrounding the adjacent portions of the filtering material, and clamping devices surrounding said washers approximately 65 at the inner edges of said end rings.

8. A filtering cell comprising an apertured core, a layer of filtering material surrounding said core, and washers extending over the ends of the core and surrounding 70 the adjacent portions of the filtering material.

9. A filtering cell comprising an apertured core, a layer of filtering material surrounding said core, and a contractile member 75 of elastic material surrounding said filtering material and tending to press it against said core.

In testimony whereof I have signed this specification in the presence of two subscribers. 80
